TELESCOPIC SIGHT

Karl Jung, Munich, Germany

Application August 8, 1929, Serial No. 384,420,
and in Germany October 22, 1928

2 Claims. (Cl. 33—50)

The object of this invention is to remove various defects in telescopic sights.

One of these defects is the comparative difficulty of aiming, and more particularly of aiming quickly, due to the distance between the ocular and the eye, a substantial spacing (generally about 80 mm.) being required by reason of the recoil on firing. Another defect is that telescopic sights are delicate instruments, easily put out of adjustment by rough handling or falling, this being particularly the case with terrestrial lens systems. In the case of prism telescopes the prisms tend gradually to become loose. Galilean telescopes have not heretofore successfully been applied to gun sights, owing to the difficulty of making the crossed wires visible, though for shooting in twilight such telescopes have a marked advantage by reason of their large aperture. A general defect of all telescopic sighting instruments heretofore in use is that they require mounting on the gun barrel, generally necessitating difficult welding operations, which are liable to injure the barrel through affecting the structure of the steel.

25 My invention aims at removing these defects without loss of efficiency in other respects.

According to the invention the telescope is mounted on the fire arm in direct contiguity to the eye of the user, the instrument having at the ocular end a shock absorbing eye-rest fitting against the bony rim of the orbita. The telescope may be anchored to the barrel or the breach by means of rails, or may be fixed to the stock without rails connecting it to the barrel. In the case of a telescope with erecting prisms, of the Porro type, the prisms and the objective may be combined to form a rigid unit, so that neither member can become loose. To enable a Galilean telescope to be used the ocular may have a fine hole, whereby a gauge on the inside of the objective is visible in the enlarged upright image of the target. For parallel adjustment there may be two parallel telescopes, a fixed distance apart, one being adapted to be pushed into the breech 45 when the bolt has been removed.

Several examples of instruments according to the invention are shown in the annexed drawing.

Fig. 1 is an elevation, partly in section, of a sight with a Porro telescope,

Fig. 2 being a cross section of the telescope on a larger scale, and

Fig. 3 a section on the line 3—3 of Fig. 1.

Fig. 4 is an elevation of a gauge used with this telescope.

Fig. 5 illustrates one method of attaching the sight to the stock of a rifle,

Fig. 6 being a vertical cross section of the stock and sight taken on lines 6—6 of Figure 5.

Fig. 7 illustrates a device for attaching the telescope to its holder.

Fig. 8 is a sectional view of the eye piece to be inflated with either air or liquid.

Referring first to Figs. 1 to 3, the prisms P, P' of the Porro telescope therein shown are rigidly fixed to a steel plate St, the prisms being within a steel casing N, which also encloses the objective O and ocular o, these parts being inseparably connected for ordinary purposes of use. The holder T of the telescope is fixed to the rifle in such position that the eye of the user is applied directly to the ocular in the same way as when using field glasses. To protect the sight from injury by recoil of the firearm there is fitted to the ocular holder a ring G of shock absorbing material, which is pressed against the bone around the orbita. This ring G may be hollow and filled with liquid, e. g. glycerine-gelatine, but it may also be solid, consisting for example of aerated rubber.

The holder T is inserted into a socket R pivoted at R¹⁰ in a cavity R¹¹ in the gun stock. A spring F presses against one wall of the socket and tends to press the latter firmly against a stop W formed by a part of the wall of the cavity R¹¹.

The gauge C shown in Fig. 4 has an elevation scale marked thereon; the divisions of the scale may be of different colours, to facilitate the reading thereof.

Figs. 1, 5 and 6 show for mounting the telescope a steel rail S sunk in a central groove in the stock H, the front end of the rail being welded, screwed or soldered to the breech. To the rear end of the rail is attached a spring f (appearing in Fig. 5) carrying a socket R, for the lower part of the telescope holder T. For steadyng the socket R there is a second spring F, which also engages the rail S, and which presses the socket and spring f firmly against a rest W, formed by part of the wall of a cavity in the stock.

According to Fig. 7 the telescope D is not directly connected to the holder, the connection being made by a spring E of substantial length, only a short part of which is free to bend. This arrangement affords additional security against injury by recoil.

Having now particularly described and ascertained the nature of my said invention and in what manner the same is to be performed, I declare that what I claim is:

2	1,946,218	
1. The combination with a gunstock and a sighting prism-telescope, of a shock absorbing support therefor, the latter being rigidly secured to the telescope and comprising a single foot re- siliently mounted in the stock so as to regain its original position whenever displaced.	to said telescope and pivotally mounted in the stock, a spring resiliently supporting said foot in the stock, said telescope being provided with an elastic cushion at one opening and disposed to have the orbita of the person sighting leaning against the said cushion of the telescope to trans- mit shocks imparted thereto partly to the orbita and partly to the shoulder of such person.	80
2. The combination with a gunstock and a sighting prism-telescope, of a single supporting foot therefor, the latter being rigidly connected	KARL JUNG.	85
